UNITED STATES PATENT OFFICE.

HARRY LANDSIEDEL, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,167,415.

Specification of Letters Patent. Patented Jan. 11, 1916.

Application filed February 8, 1913. Serial No. 747,182.

To all whom it may concern:

Be it known that I, HARRY LANDSIEDEL, a citizen of the United States, residing at Poplar Bluff, Butler county, Missouri, have 5 invented a new and useful Adding and Recording Machine, of which the following is a specification.

This invention relates to adding and recording machines of the type in which keys 10 are utilized for the purpose of setting or introducing numbers into the machine preliminary to the operation of the machine in adding and recording operations.

An object of the invention is to provide 15 automatic means for preventing the setting or introduction of numbers into the machine preliminary to adding or recording operations at selected or predetermined intervals.

Another object of the invention is to provide 20 settable mechanism whereby the keys of the machine are locked or disabled, thereby preventing the setting or introduction of numbers into the machine, at selected or predetermined intervals at the option of the 25 operator.

Another object is to equip an adding and recording machine with mechanism for automatically locking the keys of the machine to prevent operation of the keys at selected 30 or predetermined intervals, thereby preventing the setting or introduction of numbers into the machine until said key-locking mechanism has been released.

In commercial use it is frequently desirable 35 to list the items in parallel columns upon a single sheet of paper, for instance, and it is desirable that each of the several columns shall contain an equal number of items. For example it may be desirable that 40 each column contain twenty-five items.

The present invention comprises mechanism 45 for automatically locking or disabling the keys of the machine when the selected number of items have been listed in a column, thereby mechanically and positively protecting the operator from error by rendering it impossible for the operator to set up or introduce into the machine an excessive number of items for any of the several 50 columns.

A further object of the invention, therefore, is to equip the machine with mechanism settable at the option of the operator to lock or disable the keys when a selected predetermined number of items have been 55 set up or introduced into the machine.

Other object will appear from the following detailed description, reference being made to the accompanying drawing in which I have illustrated one embodiment of my 60 invention and in which—

Figure 1 is a longitudinal sectional view of a Dalton adding and listing machine illustrating such of the mechanical parts of the machine as essentially coöperate with 65 my invention. Fig. 2 is a sectional view approximately along the line 2—2 of Fig. 1, omitting the parts of the machine which do not coöperate with my invention. Fig. 3 is a plan view of the machine illustrating 70 the settable device which is adjustable or settable, at the will of the operator, to lock or disable the keys when any selected or predetermined number of items have been added or listed. Fig. 4 is a perspective view 75 of the key locking devices and the train of connections whereby the key locking devices are set when the last one of a predetermined number of items has been added or listed. Fig. 5 is a detailed sectional view of the 80 settable device which actuates the train of connections to the key locking mechanism. Fig. 6 is a perspective view of a retaining or holding hook or pawl constituting one of the elements of my invention in the embodiment illustrated.

For purposes of convenience I have illustrated the present embodiment of my invention in the Dalton adding machine, which is manufactured in substantial conformity with 90 Hopkins' Patent No. 1,039,130, dated September 24, 1912. The said Dalton machine, as it is now in commercial use and as described and illustrated in said Hopkins' Patent No. 1,039,130, includes a series of 95 numeral keys 1 arranged in suitable relation in a key-board and mounted upon levers 2, which extend toward the rear of the machine, and which are operable in the well understood manner to set up numbers in a 100

carriage 3, preliminary to the adding or listing of said numbers. The numbers which are set up or introduced into the carriage 3, by depression of the keys 1, are recorded by operation of the type-carriers 4, and may be added by the adding wheels 5 through the movement of the racks 6 which coöperate with the type-carriers, the movement of the type-carriers and racks being determined by the parts in the carriage which represent the numbers set up or introduced into the carriage by operation of the numeral keys. It is well understood that the operation of the type-carriers and racks, for adding and listing purposes, is controlled by the rocking of a shaft 7, which is rocked forwardly to permit forward movement of the racks and type-carriers and which is rocked rearwardly to restore the racks and type-carriers to their idle positions. The mechanism for effecting these operations may be of any preferred construction and arrangement, or the shaft 7 may be rocked in one direction by a handle 8 and in the other direction by springs 9. It is necessary to move the racks and type-carriers forwardly and rearwardly for each item listed or added, so that it is also necessary to rock the shaft 7 forwardly and backwardly for each item listed or added.

The paper is fed to the type-carriers around a platen 10 mounted in a laterally movable carriage 11 so that different columns of the paper may be presented to the type-carriers, thereby enabling the operator to list numbers in parallel columns on the same sheet of paper.

The mechanism above described is substantially the same as that contained in the Dalton machine and as described in detail in the Hopkins patent referred to. It being understood, then, that reciprocation of the type-carriers and racks is necessary for each item recorded or added, and that operation of the shaft 7 is also necessary for each item recorded or added, no further detailed description of the structure of the Dalton adding machine or of the structure of the machine of the Hopkins patent aforesaid appears necessary. It is with these existing and well understood portions of the Dalton machine and the machine of the Hopkins Patent No. 1,039,130, that I have illustrated my invention which will now be described.

55 A link 12 has its lower end pivoted to an arm 13 attached to the shaft 7 and its upper end having pin-and-slot connection 14 with the forwardly extending arm of a bell-crank lever 15, which is pivotally supported upon a shaft 16. The upwardly extending arm of the lever 15 carries a laterally extending portion 17 upon which is pivoted an actuating pawl 18. A spring 19 is arranged to actuate the upper arm of the bell-crank lever 15 rearwardly and a spring 20 connect-

ing the rear end of the actuating pawl 18 with a stationary element, actuates the forward end of said pawl 18 into engagement with the ratchet wheel 21 upon which said pawl acts.

The ratchet wheel 21 is attached to a flange on the lower end of the sleeve 22. The sleeve 22 has a flange 23 fitting within an opening in the top of the case of the machine, and a removable plate 24 threaded upon the upper extremity of said sleeve also extends into the opening in the case of the machine, said flange and said plate constituting a journal having bearing within the opening in the case into which they extend. The extent of rotation of the sleeve 22 is limited or defined by a projection 25 on the flange 23, and a projection 26 on the case of the machine extending into the path of movement of the projection 25, and constituting an abutment to limit or define the extent of rotation of the sleeve 22. The normal or idle position of the parts, when they are set to permit the maximum rotation of the sleeve 22, is that illustrated in Fig. 2, in which the projection 25 rests against the outer or right hand side of the projection 26. A motor spring 27 mounted between the flange 23 and plate 24, within the opening in the case, actuates the sleeve 22 toward its idle position in which the projection 25 is against the outer or right-hand side of the projection 26, so that when the sleeve 22 is turned anti-clockwise, the spring is wound or tensioned.

Since the actuating pawl 18 is moved rearwardly on the forward rocking of the shaft 7 in any recording or adding operation of the machine, and is moved forwardly on the return movement of the shaft 7, the said pawl 18 will rotate the ratchet wheel 21 step by step. It is, as a result of this operation, that the keys are locked at any predetermined time, the locking mechanism being actuated directly as a result of the movement of the ratchet wheel 21.

A rod or spindle 28 is revolvably mounted in the sleeve 22. Said rod or spindle is also longitudinally movable, and is provided on its upper end with a knob 29 which constitutes means for manual engagement as required for setting the key locking devices to lock the keys at the desired predetermined intervals. A spring 30 is interposed between the notch 29 and the upper extremity of the sleeve 22, thereby yieldingly supporting the rod or spindle in its normal and elevated position. To the lower end of the rod or spindle 28 an arm 31 is attached. The arm 31 supports a cam block 32, and two bores or recesses are formed within said cam block. Each of said bores or recesses retains a coil spring 33 which encircles the lower ends of the latch bolts or pins 34 whose upper ends extend into and

through holes in the arm 31. Ribs or flanges 35 on said latch bolts or pins 34 rest upon the upper ends of the spring 33, so that said springs actuate said latch bolts or pins upwardly; said flanges also engage against the under side of the arm 31 in order to limit upward movement of said bolts or pins. The bolts or pins 34 are on the same radial line from the center of the rod or spindle 28, one of said bolts or pins also being nearer than the other to said rod or spindle. Two annular series of holes 36 are formed in the ratchet wheel 21, in this instance each series or annular row of holes 15 include 53 holes. The holes 36 of one row or series are in staggered relation, that is on different radial lines in the ratchet wheel, with respect to the holes 36 in the other annular row or series. The protruding ends 20 of the pins or bolts 34 are adapted to engage in the holes 36 and thereby lock or latch the cam block 32 and the ratchet wheel 21 together. Because of the staggered relation of the holes 36 of one row or series with 25 respect to the holes of the other row or series, and because there are 53 holes in each row or series, it is obvious that there are 106 possible adjustments of the cam block 32 with respect to the ratchet wheel 21.

30 A plate or disk 37 is attached to the top of the case of the machine over the plate 24 and is provided with an annular scale or indicator upon its upper surface adapted, by coöperation with a pointer 38 keyed on the rod or spindle 28 above the end of the sleeve 22, to register or indicate the position of the cam block 32, thereby designating the number of items which may be added or recorded before the keys become locked.

35 These devices enable the operator to adjust the locking mechanism precisely so that any desired number of items within the capacity of the mechanism may be added or recorded in each of the several columns.

40 As previously explained, each operation of the shaft 7 effects a step movement of the ratchet wheel 21, and also of the cam block 32 which is in locked engagement with the ratchet wheel. After the predetermined 45 number of step movements of the ratchet wheel and the cam block have occurred, the cam block engages or contacts with the upwardly extending end of the bell-crank lever 39. A lever 40 connects the opposite end arm 50 of the bell-crank lever 39 with an arm 41 attached to a rock shaft 42, properly supported with respect to the key levers 2. The connection between the link 40 and the arm 41 is a pin-and-slot connection 43, a spring 44 holding the arm 41 at the upper extremity of the slot. A plate 45 is supported by the base of the machine transversely of the key levers 2, and is provided with a series of notches or slots 46 within which the key 55 levers operatively extend. Locking plates 47 are pivotally supported by the plate 45 between the notches 46, the lower ends of said plates being provided with shoulders 48 against which the key levers 2 engage when depressed. Therefore, when any key 70 lever 2 is depressed it engages the shoulder 48 of the locking plates at each side of said key lever, actuating the locking plates laterally, and preventing the depression of any other key until the locking plates are released. A slide plate 49 is supported by the plate 45, and is provided with an arm or projection 50 adapted to be moved to engage with the locking plate 47 at one end of the series and thereby prevent movement of any 75 of the locking plates and lock all of the keys against operation. A spring 51 yieldingly holds the locking plate 49 in position so that the projection 50 is out of contact with the locking plate 47, thereby normally permitting any of the keys to be depressed. An arm 52 is attached to the rock shaft 42 and carries a cam member 53 which extends through a slot in the plate 45. When the cam block 32 depresses the horizontal arm 90 of the lever 39 in the operation of the machine for listing or adding purposes, as above explained, the shaft 42 is rocked, thereby moving the cam plate 53 through the slot in the plate 45 and against a shoulder 95 54 on the slide plate 49, thereby actuating or moving the slide plate 49 laterally and causing the projection 50 to engage against the locking plate 47 at the end of the series and thereby lock all of the locking 100 plates to prevent operation of any of the numeral keys.

From the foregoing description it will be seen that the operator may selectively set the locking devices so that the keys will be 105 locked at any predetermined time, or after any predetermined number of items have been added or listed, within the capacity of the item counting or indicating devices 37-38. It is also clear that the keys are 110 automatically locked when the last item of the desired predetermined number of items is listed or added in any one of the several columns, or in a single column, as the case may be. As previously mentioned, the carriage and platen 10 are laterally movable for the purpose of presenting different columns of the paper to the recording mechanism. Any suitable, or known, carriage retaining or holding devices may be employed, such, for instance, as those illustrated and described in the Hopkins patent aforesaid, but since the form of the carriage retaining and holding devices constitute no part of the present invention such devices are not herein 115 illustrated. It is sufficient for the purpose of this application to understand that the carriage and platen remains laterally immovable until the desired number of items have been listed or added in each of the several 120 125 130

- columns, and after the desired number of items have been listed or added the carriage is moved laterally to present another column of the paper to the recording mechanism.
- 5 The lateral movement of the carriage and platen involves the rocking of a rod or shaft 54 (Fig. 1), by means of a lever 55 or other suitable device. The rod 54 presents a flat surface against the upper end of a lever 56 which is pivotally mounted upon a support 57 on a stationary member, so that when the rod 54 is rocked the lower end of the lever 56 is moved forwardly. The lower end of the lever 56 rests against the rear extremity of an actuating element 58 which is upheld by supports 59 attached to the case or some other part of the machine. The actuating element 58 is longitudinally movable on the supports 59.
- 10 At each stepping movement of the ratchet wheel 21 said wheel is engaged and retained by a retaining pawl 60 supported upon a stationary support 61 and actuated into engagement with the ratchet wheel 21 by a spring 62, connecting an arm of said pawl with the support on each pawl. The forward end of the actuating element 58 presents a beveled or oblique surface against a projection on the pawl 60, so that forward movement of the actuating element 58 releases the pawl 60 from the ratchet wheel 21. A projection 63 on the element 58 engages behind an arm on the actuating pawl 18, so that forward movement of the element 58, 15 in addition to releasing the pawl 60, also releases the pawl 18 from the ratchet wheel 21. The two pawls are thus released from the ratchet wheel 21 at each lateral movement or column spacing of the carriage and platen. When the two pawls are thus released the motor spring 24, (Fig. 1) restores the sleeve 22 and the ratchet wheel 21 to idle position in which the projection 25 (Fig. 2) is against the right hand side of the projection 26. This adjustment permits the listing and adding of the same number of items as were listed or added in the previous column, and after an equal number of items have been listed or added in the newly 20 positioned column, the keys are again automatically locked against operation as in the previous instance. When the carriage or platen is positioned to present a new column of the paper to the recording mechanism 25 the rod 54 resumes its normal position, as shown in Fig. 1, and the springs 20 and 62 again engage the pawls 18 and 60, respectively, with the ratchet wheel 21, and also exert a backward pressure upon the actuating element 58 sufficient to restore said element and the lever 56 to idle position.

During certain operations of the machine it is desirable that the item counting or indicating devices 37—38, and the train of key locking, be prevented from operating.

In order to prevent operation of the item counting or indicating device and the train of key locking devices it is only necessary to disable either the pawl 18 or the pawl 60, or some other part of the train of operating 70 connections. In the present instance I have illustrated a device for disabling the pawl 60, by disengaging said pawl 60 from the ratchet wheel 21, so that when the actuating pawl 18 is reciprocated the ratchet wheel 21 will oscillate or rock with the pawl 18; inasmuch as forward movement of the pawl 18 actuates the ratchet wheel in one direction, and when the pawl 18 moves backwardly the 75 spring 24 actuates the ratchet wheel in the 80 other direction and causes said ratchet wheel to follow the pawl 18 in its oscillating movements. The device for effecting disengagement of the pawl 60 from the ratchet wheel 21 comprises a screw 63 operatively extending through a hole in the case, and having its inner end adjacent to a projection or arm on the pawl 60. A suitable handle or knob 64 on the outer end of the screw 63 constitutes means for manual engagement for the 85 purpose of operating the screw 63 effectively to disengage the pawl 60 from the ratchet wheel 21, all of which is obvious in the illustration of these elements in Fig. 2.

I have illustrated the present embodiment 95 of my invention selectively settable at the will of the operator to lock the keys against operation, automatically, after a predetermined number of items have been listed or added, the locking mechanism being actuated or controlled by the main shaft of the machine. It is obvious, however, that the locking mechanism may be otherwise actuated, and it is only material or essential that the machine be disabled at predetermined periods. It is not material that the devices be of the specific form or arrangement, nor that they be actuated in the specific manner, shown and described, for various modifications and alterations will readily suggest themselves to those skilled in the art to which the invention relates. I do not restrict myself to specific features, but

What I claim and desire to secure by Letters Patent of the United States is:

1. In an adding machine, the combination with depressible keys for setting up numbers and a laterally movable carriage movable to different column positions, of devices 120 for locking the keys to prevent depression thereof, and mechanism controlled by said carriage when released for column movement for unlocking the keys.

2. In an adding machine, the combination 125 of depressible keys, a carriage movable to and settable in different column positions, elements for engaging and preventing depression of said keys under predetermined conditions, means for releasing the carriage 130

for movement to different column positions, and means controlled by the carriage when released for such movement for unlocking the keys.

5 3. In an adding machine, the combination of depressible numeral keys, a paper carriage movable to different column positions, devices preventing depression of the keys at the end of each column, and means controlled by the movement of the carriage to another column position for releasing said devices to permit depression of the keys.

10 4. In an adding machine, the combination of depressible keys operable to set up numbers, mechanism for locking said keys at the end of each column, a carriage movable to different lateral column positions, means for holding said carriage in its different column positions, means for releasing said carriage for column movements, and means controlled by said carriage when released for column movement for unlocking said keys.

15 5. In an adding machine, the combination of keys operable to set up numbers, a carriage movable to different column positions, means for locking said keys at the end of each column, means for varying the length of the column which will be recorded before said locking means will lock said keys, means for holding said carriage in its different column positions, means for releasing said carriage for column movement, and connections controlled by said carriage when released for column movement for unlocking the keys irrespective of the length of the column.

20 6. In an adding machine, the combination of keys operable to set up numbers, a carriage movable to different column positions, elements for locking said keys, mechanism for causing said elements to lock said keys at the end of any column, and means controlled by the operation of said paper carriage to unlock said keys and restore said mechanism to its starting point.

25 7. In an adding machine, the combination of keys for setting up numbers, a laterally movable carriage movable to different column positions, devices for locking the keys at the end of each column, mechanism controlling said carriage, and mechanism controlled by the positioning of said carriage to another column position for unlocking the keys.

30 8. In an adding machine, the combination of depressible keys operable to set up numbers, a series of plates, mechanism for recording the numbers set up by said keys, a carriage arranged to feed paper to said recording mechanism and movable to different column positions, means for holding said carriage in its different column positions, means for holding said plates to prevent operation of said keys at the end of each

35 column, a device for releasing said carriage for column movement, and mechanism controlled by the release of said carriage for releasing said plates to enable said keys to be operated after said carriage reaches another column position.

40 9. In an adding machine, the combination of keys operable to set up numbers to be added and recorded, a carriage movable to different column positions, recording mechanism operable to record on paper in said carriage the numbers set up by said keys, a device for holding said carriage in its different column positions, mechanism for locking the keys at the end of each column, manually operable devices for releasing said carriage for movement to another column position, and connections controlled by the release of said carriage for unlocking the keys.

45 10. In an adding machine, the combination of keys for setting up numbers to be added and recorded, recording mechanism operable to record the numbers set up by said keys, a shaft controlling said recording mechanism, a carriage arranged to feed paper to said recording mechanism and movable to different column positions, a device for holding said carriage in its different column positions, mechanism actuated by said shaft for locking said keys at the end of each column, means for releasing said carriage for column movement, and means controlled by said carriage when released for locking movement for unlocking the keys.

50 11. In an adding machine, a series of keys, a series of plates movable by operation of said keys, an element settable to prevent movement of said plates and thereby locking said keys, a device for setting and holding said element in position to prevent movement of said plates, connections for operating said device, and means indicating when said device is in position to hold said element to prevent movement of said plates.

55 12. In an adding machine, a series of depressible keys, a series of pivoted plates movable by depression of any of said keys, an element adjustable to prevent movement of said plates and thereby lock said keys, an actuator for moving said element to the position aforesaid, connections controlling the operation of said actuator, and means indicating whether or not said actuator is in position to hold said element to prevent movement of said plates.

60 13. In an adding machine, a series of depressible keys, a series of plates for locking said keys, an element movable to and from position to cause said plates to lock said keys, an adjustable actuator controlling said element, means for setting said actuator in position to actuate said element at a predetermined occasion, means indicating the position of said actuator, means for holding

- said actuator in its different positions, means for releasing said actuator, and means for restoring said actuator to its starting point.
14. In an adding machine, the combination with mechanism for recording numeral items, a shaft controlling said recording mechanism, mechanism actuated by said shaft to indicate the number of items recorded and a device for holding said indicating mechanism in various adjustments, of a laterally movable carriage arranged to feed paper to said recording mechanism and means for holding said carriage in different column positions, a manually operable device for releasing said carriage, and connections operated by said device for releasing the holding device for said indicating mechanism.
15. In an adding machine, the combination of depressible keys operable to set up numbers, mechanism for recording numbers set up by said keys, a shaft controlling said recording mechanism, a device actuated by said shaft to indicate how many numbers have been recorded, settable devices operated by said indicating mechanism to prevent depression of said numeral keys, means for predetermining how many numbers may be recorded before said devices will be set to prevent depression of the keys, and means for disabling said indicating mechanism and said devices at the will of the operator.
16. In an adding machine, the combination with depressible keys operable to set up numbers, plates for preventing depression of said keys, mechanism for recording the numbers set up by said keys, a carriage arranged to feed paper to said recording mechanism, a lever controlling said carriage, and means operable incidentally to the operation of said recording mechanism and independently of said carriage to hold said plates in position to prevent depression of said keys, of means controlled by said lever to release said plates.
17. In an adding machine, the combination with depressible keys for setting up numbers to be added and recorded, recording mechanism operable to record the numbers set up by said keys, a shaft controlling said recording mechanism, a carriage arranged to feed paper to said recording mechanism, connections for operating said indicating means from said shaft, and a lever controlling said carriage, of means indicating the number of items recorded, devices actuated by said indicating means for locking said keys against operation when a predetermined number of items have been recorded, means controlled by said lever for releasing said keys, and means for restoring said indicating mechanism to its starting point.
18. In an adding machine, the combination with mechanism for recording numeral items, a shaft controlling said recording mechanism, mechanism actuated by said shaft to indicate the number of items recorded, and a device for holding said indicating mechanism in various adjustments, of a laterally movable carriage arranged to feed paper to said recording mechanism and movable laterally independently of said indicating mechanism, a lever controlling lateral movement of said carriage, and means actuated by said lever incidentally to lateral movement of said carriage to release said holding device, and an actuating device for restoring said indicating mechanism to its starting point.
19. In an adding machine, the combination with depressible numeral keys operable to set up numbers, mechanism operable to record the numbers set up by said keys, a shaft controlling said recording mechanism, a carriage arranged to feed paper to said recording mechanism, a lever controlling said carriage, and means actuated incidentally to the operation of said recording mechanism for locking said keys at predetermined intervals independently of the movement of said carriage, of means controlled by said lever for unlocking said keys, substantially as specified.
20. In an adding machine, the combination with depressible numeral keys operable to set up numbers, plates for preventing depression of said keys, a sliding element controlling said plates, mechanism for recording the numbers set up by the operation of said numeral keys, a shaft controlling said recording mechanism, actuating devices for moving and causing said element to hold said plates and prevent depression of said numeral keys at predetermined intervals incidentally to the operation of said recording mechanism, means for operating said actuating devices from said shaft, and means for restoring said element to idle position, of means for disabling said actuating devices at the will of the operator.
21. In an adding machine, the combination with depressible numeral keys operable to set up numbers, mechanism for recording the numbers set up by said keys, a shaft controlling said recording mechanism, mechanism actuated by said shaft to indicate how many numbers have been recorded, and key-controlling devices operated by said indicating mechanism to prevent depression of said numeral keys at predetermined intervals, of means for disabling said indicating mechanism and key-controlling devices at the will of the operator.
22. In an adding machine, the combination with keys and locking devices therefor, of a carriage movable to different lateral column positions, and mechanism controlled by movement of said carriage for unlocking said keys.
23. The combination with key locking de-

vices and a carriage movable to different lateral column positions, of mechanism controlled by said carriage for releasing said locking devices.

5 24. The combination with numeral keys and elements arranged to engage said keys, of means for holding said elements to prevent operation of said keys, a carriage movable to different column positions, and de-

vices controlled by said carriage for releasing said means.

In witness whereof, I have signed this specification in the presence of two subscribing witnesses.

HARRY LANDSIEDEL.
